UNITED STATES PATENT OFFICE.

JOHN PETERSON, OF BUFFALO, NEW YORK.

DESIGN FOR A TABLET OR LOZENGE.

No. 37,874.

Specification for Design.

Patented March 6, 1906.

Application filed January 16, 1906. Serial No. 296,428. Term of patent 14 years.

To all whom it may concern:

Be it known that I, JOHN PETERSON, a citizen of the United States, residing at Buffalo, in the county of Erie and State of New York, have invented a new, original, and ornamental Design for Tablets and Lozenges, of which the following is a specification.

In the accompanying drawing the figure is a perspective view of a tablet or lozenge embodying my invention.

I claim—

The ornamental design for a tablet or lozenge, as shown.

JOHN PETERSON.
